UNITED STATES PATENT OFFICE

2,479,193

ARTICULATED CATHODE

William P. Zabel, Cleveland Heights, Ohio, assignor to General Electric Company, a corporation of New York

Application July 8, 1946, Serial No. 681,809

10 Claims. (Cl. 250—27.5)

1

My invention relates to electric discharge devices, and more particularly to cathodes for such devices.

Among the objects and advantages of my invention are the provision of a cathode which is inexpensive to manufacture, is adaptable to high speed automatic production and to automatic machine mounting of the cathode on its supports, ease of application of electron emissive material thereto and uniformity of the coating of emissive material on the cathode, and faster and easier starting of an electrical discharge from the cathode. Further objects and advantages of my invention will appear from the following description of species thereof and from the drawing.

In the drawing Fig. 1 is a greatly enlarged side view showing the coiling of a cathode on a mandrel in accordance with my invention; Fig. 2 is an end view of the coil and mandrel; Fig. 3 is a greatly enlarged side view of a finished and mounted cathode; and Fig. 4 is an elevation of one end of a gaseous electric discharge device containing such a cathode.

The cathode comprising my invention may be referred to as an articulated cathode composed of a jointed or chain-like series of spaced helically coiled segments or body sections connected together by open pitch windings of the material being coiled. The segments and spaces or gaps are usually short in relation to total cathode length.

Referring to Fig. 1, the species illustrated therein comprises three parallel tungsten wires 1 continuously coiled around a pair of parallel steel mandrels 2 in short segments 3 which are spaced apart by spaces or gaps 4 consisting of an open pitch turn of the wires 1. The continuous coil is then heat treated to set the wires 1, after which it is severed through certain of the gaps 4 to form individual cathodes composed of a desired number of segments 4 which is at least four but preferably six or eight or more.

The mandrels 2 are then dissolved in a suitable acid solution, whereupon there is a recoil of the turns to a sort of corkscrew or spiral fluted outline as illustrated in Figs. 3 and 4. After another heat treatment to completely remove strains and clean the wire, the coil is mounted by clamping the outermost segments in hooks 5 in lead-in wires 6 extending from a conventional stem 6, after which the said leads 5 are separated to stretch the coil to provide a spacing of about one mil between adjacent turns of the outer wires in the group of wires 1.

5 The coil is then provided with a coating 5' of a suspension of alkaline earth carbonates which is applied to the segments 3 exclusive of the two end segments. The suspension may be applied by a trough-shaped applicator similar to that disclosed in Patent 2,363,055, J. Flaws. It will be seen in Fig. 3 that the coating material does not fill or plug the spaces or gaps 4 of the cathode coil.

10 The stem 6 is then sealed to the end of a bulb 7, there being one such stem at each end of a tubular bulb in the case of the well-known fluorescent lamps. The bulb 7 is subsequently exhausted and current passed through the leads 5 to heat the coil and cause the alkaline earth carbonates to be broken down to the corresponding oxides, after which the bulb is filled with a suitable gaseous atmosphere such as a few millimeters of argon and a few drops of mercury. Such fluorescent lamps are operated at a current of the order of 100 milliamperes to 1½ amperes with a mercury vapor pressure, during operation, of the order of 10 microns. When the lamp is to be operated in an instant starting circuit, that is without preheating the cathodes, the cathodes may be shunted in any suitable manner, as by twisting the leads together outside the bulb 7.

15 By way of example, in the case of a cathode of the type described above for a 40 watt fluorescent lamp, each of the segments 3 consisted of ten turns of three parallel 1.8 mil tungsten wires 1 in a band continuously coiled close together over two parallel 15 mil steel mandrels, the segments being about 1½ mm. long. Eight of these segments separated by ½ mm. gaps 4 constituted a cathode. The suspension of emissive material was applied to the six segments between the leads 5 and did not flow by capillary action past the end gaps 4 adjacent the clamped segments. 20 This is highly desirable because any emissive material deposited on the leads cannot be properly activated upon subsequent passages of current through the cathodes.

25 It is to advantage to provide a multiplicity of segments 3. In automatic machine mounting it is possible that in some cases the coil may be clamped at the end gap 4 inside the endmost segment 3, but with a sufficient number of segments the electrical characteristics of the cathode will not be too greatly affected and the next to the last gap 4 will then act as a barrier to travel of the emission mixture toward the lead wire, the next to the last segment being uncoated. Thus, for example, by doubling the number of 30 spaces and segments described above, it will be

assured that regardless of where the ends of the cathode are clamped (within the limits of accuracy of the ordinary machine) there will be a space of $\frac{1}{2}$ mm. to $\frac{3}{4}$ mm. away from each lead to stop the flow of emission mixture into the lead wire clamps. Intermediate spaces provide easy entrance of the emission material into the segments without plugging them or the spaces therebetween when the consistency of the mixture is correctly adjusted.

In a variation of the structure described above, I have made articulated cathodes with seven tungsten wires of one mil diameter wound side by side simultaneously in bands or segments approximately 1.4 mm. wide separated by $\frac{1}{2}$ mm. spaces. Some of these "septet" cathodes were wound on two 15 mil steel mandrels, and others on two 21 mil mandrels. In other cases three, four and five multiple wire windings in articulated arrangement were made from 1.5 mil wire wound on two 15 mil mandrels with segments and spaces similar in length to those of the septet cathodes.

Among the advantages to be expected of the articulated cathode structure are faster and easier starting of the electric discharge therefrom than from a single long body segment. In starting, a glow first appears at the exterior of the cathode and then shifts to the interior of the cathode. It is desirable that the shift be made very rapidly. It is known that ordinary cathodes composed of a single long segment give hard starting when the ends are plugged with emission material because the glow cannot readily enter until that material has been hollowed out at one end or the other. It therefore may be concluded that the greater the number of openings present the better chance the glow has to choose for its entrance the most favorably located and activated segment. For instance, in a sixteen segment articulated cathode at least twenty-four ends will be available on twelve segments as compared with two ends on one long segment.

Other advantages include the following. Faster coiling with increased number of spaces and reduced cost of cathodes due to reduction of the amount of tungsten wire needed and increased machine output. Universal adaptation of the same cathode design to lamps or other discharge devices of different rating by simply cutting off the desired length for proper number of segments. Good axial alignment of multiple windings because of different reactions or recoil in spaces and segments during mandrel dissolving and final heat treating. Coils do not tangle with each other and roll easily even though they have a spiral fluted contour. Good internal coating of short segments with emission material which can readily flow in and out of the short cylinders or segments, thereby reducing probability of plugging. The open spaces are instrumental in helping drain out excess material from the segments. Precise adjustment of cathode location on the mounting machine with respect to end segments is unnecessary if segments are very short. Quick drying of emission material and good distribution of the same within short segments. Thorough and fast "degassing" of the cathode during lamp exhaust because of the many short open end cylinders from which gas may escape without interference. More uniform heating and activation of cathodes during exhaust.

What I claim as new and desire to secure by Letters Patent of the United States is:

1. A cathode for electric discharge devices comprising a helical wire coil composed of a multiplicity of relatively short closely coiled segments of at least several turns of wire spaced apart by open pitch sections and a coating of electron emissive material on and within said segments, the spaces between segments being open and unbridged by said coating material.

2. A cathode for electric discharge devices comprising a helical coil of a plurality of parallel wires composed of a multiplicity of relatively short closely coiled segments of at least several turns of wire spaced apart by open pitch sections and a coating of electron emissive material on and within said segments, the spaces between segments being open and unbridged by said coating material.

10 3. A cathode for electric discharge devices comprising a helical wire coil composed of a multiplicity of relatively short closely coiled segments of at least several turns of wire spaced apart by open pitch sections and a coating of electron emissive material on and within said segments, the spaces between segments being open and unbridged by said coating material.

15 4. A cathode for electric discharge devices comprising a helical coil of a plurality of parallel wires composed of a multiplicity of relatively short closely coiled segments of at least several turns of wire spaced apart by open pitch sections and a coating of electron emissive material on and within said segments, the spaces between segments being open and unbridged by said coating material.

20 5. A cathode for electric discharge devices comprising a helical wire coil composed of a multiplicity of relatively short closely coiled segments of at least several turns of wire of oval cross section spaced apart by open pitch sections and having a spiral fluted contour and being coated with electron emissive material.

25 6. A cathode for electric discharge devices comprising a helical coil of a plurality of parallel wires composed of a multiplicity of relatively short closely coiled segments of at least several turns of wire of oval cross section spaced apart by open pitch sections and having a spiral fluted contour and being coated with electron emissive material.

30 7. A cathode for electric discharge devices comprising a singly coiled wire helix composed of a multiplicity of relatively short closely coiled segments of at least several turns of wire spaced apart by open pitch sections and a coating of electron emissive material on and within said segments, the spaces between segments being open and unbridged by said coating material.

40 8. A cathode for electric discharge devices comprising a singly coiled helix of a plurality of parallel wires composed of a multiplicity of relatively short closely coiled segments of at least several turns of wire spaced apart by open pitch sections and a coating of electron emissive material on and within said segments, the spaces between segments being open and unbridged by said coating material.

45 9. A cathode comprising a helical wire coil composed of a multiplicity of relatively short closely coiled segments of at least several turns of wire spaced apart by open pitch sections and a coating of electron emissive material on and within said segments, the spaces between segments being open and unbridged by said coating material, the individual turns in said segments being spaced apart a distance of the order of a mil.

50 10 10. A cathode comprising a helical coil of a plurality of parallel wires composed of a multiplicity of relatively short closely coiled segments of at least several turns of wire spaced apart by open pitch sections and a coating of electron emissive material on and within said segments, the spaces between segments being open and unbridged by said coating material, the individual turns in said segments being spaced apart a distance of the order of a mil.

55 11. A cathode comprising a helical coil of a plurality of parallel wires composed of a multiplicity of relatively short closely coiled segments of at least several turns of wire of oval cross section spaced apart by open pitch sections and a coating of electron emissive material on and within said segments, the spaces between segments being

open and unbridged by said coating material, the individual turns in said segments being spaced apart a distance of the order of a mil.

10. A cathode for electric discharge devices comprising a linear helical wire coil composed of a multiplicity of relatively short closely coiled segments of at least several turns of wire spaced apart by open pitch sections and a coating of electron emissive material on and within said segments, the spaces between segments being 10 open and unbridged by said coating material.
